INVENTOR
John T. Bender
BY
Frank W. Bond
ATTORNEY.

UNITED STATES PATENT OFFICE.

JOHN T. BENDER, OF CANTON, OHIO.

PLOW-JOINTER.

SPECIFICATION forming part of Letters Patent No. 445,281, dated January 27, 1891.

Application filed September 24, 1890. Serial No. 365,980. (No model.)

To all whom it may concern:

Be it known that I, JOHN T. BENDER, a citizen of the United States, residing at Canton, in the county of Stark and State of Ohio, 5 have invented certain new and useful Improvements in Plow-Jointers; and I do hereby declare that the following is a full, clear, and exact description of the same, reference being had to the annexed drawings, making 10 a part of this specification, and to the letters of reference marked thereon, in which—

Figure 1 is a side view of a plow, showing my jointer properly attached thereto. Fig. 2 is a view of the jointer-head, showing the 15 jointer-arms properly attached together, and the mold-board and jointer-point. Fig. 3 is a detached view of the jointer-head. Fig. 4 is a detached view of one of the jointer-arms. Fig. 5 is a detached view of the jointer mold-board. Fig. 6 is an edge view of the jointer-point. Fig. 7 is a face view of the jointer-point. Fig. 8 is a detached view of the lower 20 jointer-arm.

The present invention has relation to plow-jointers; and it consists in the different parts and combination of parts hereinafter described, and particularly pointed out in the 25 claims.

Similar letters of reference indicate corresponding parts in all the figures of the drawings.

In the accompanying drawings, A represents the jointer-head, which is clamped to a plow-beam by means of the clamping-bolts *a* 35 and the cross-bar *b*. The upper jointer-arm *B* is attached to the jointer-head *A* by means of the clamping-bolt *c*.

For the purpose of adjusting the jointer proper up and down the top or upper end of 40 the jointer-arm *B* is convex, which fits the corresponding concaved portion of the jointer-head *A*. The elongated slot *C* is provided, which is for the purpose of allowing the jointer-arm *B* to be swung back and forth 45 within the limits of the elongated slot *C*, and thereby adjust the jointer proper up or down and to or from the plow proper. The lower jointer-arm *D* is bolted to the upper jointer-arm *B* by means of the clamping-bolt *d*, and 50 for the purpose of providing a vertical ad-

justment of the jointer proper the elongated slot *e* is provided. To the lower portion of the lower jointer-arm *D* is bolted or otherwise attached the mold-board *E*, which mold-board is located as illustrated in Figs. 1 and 55 2. The point *F* is bolted or otherwise attached to the jointer-arm *D* below the mold-board *E*, and is located substantially as illustrated in Figs. 1 and 2.

For the purpose of providing a point having three cutting-points, the point *F* is made in the form of a triangle, thereby providing the three points *f*. It will be understood that in use the lower point *f* will become worn and dull, and thereby unfit for use, at which 60 time the point *F* can be loosened and a new point *f* brought into position for use, and so on until the entire three points *f* are worn out, thus providing in a single point or piece 65 three working-points. If desired, the point 70 *F* may be formed convexo-concave, the curvature of said point *F* corresponding substantially with the curvature of the mold-board *E*.

For the purpose of adjusting the jointer proper laterally the elongated slot *g* is provided. 75

Having fully described my invention, what I claim as new, and desire to secure by Letters Patent, is—

1. The combination of the jointer-head *A* 80 and means for attaching said jointer-head to a plow-beam, the arm *B*, provided with a convex end received by a corresponding concaved portion of the jointer-head *A*, the elongated slot *C*, the clamping-bolt *c*, the jointer-arm *D*, adjustably attached to the jointer-arm *B*, the mold-board *E*, and the point *F*, substantially as and for the purpose specified. 85

2. The combination of the head *A*, the arms *B* and *D*, and the triangle-point *F*, provided 90 with the points *f*, substantially as and for the purpose specified.

In testimony that I claim the above I have hereunto subscribed my name in the presence of two witnesses.

JOHN T. BENDER.
